UNITED STATES PATENT OFFICE.

CARL A. VONDERHEID AND HERBERT L. EDDY, OF OIL HILL, KANSAS.

BOILER-FRUE CLEANER OR SCALER.

Application filed May 26, 1921. Serial No. 472,660.

To all whom it may concern:

Be it known that we, CARL A. VONDERHEID and HERBERT L. EDDY, citizens of the United States, residing at Oil Hill, in the 5 county of Butler and State of Kansas, have invented certain new and useful Improvements in a Boiler-Flue Cleaner or Scaler; and I do hereby declare the following to be a full, clear, and exact description of the 10 invention, such as will enable others skilled in the art to which it appertains to make and use the same.

The object of the invention is to provide a simple and efficient apparatus by means 15 of which boiler flues, such as those used in fire tube boilers can be scaled and cleaned with facility and efficiency with the least possible effort upon the part of the operator or attendant and with an expedition 20 which is impossible by pursuing the methods which are now in common use and which are dependent upon a manual scraping of the scale which ordinarily adheres rather tenaciously to the surfaces of the 25 tubes or flues; and with this object in view the invention consists in a construction, combination and relation of parts of which a preferred embodiment is shown in the accompanying drawings, wherein:

30 Figure 1 is a general view of an apparatus embodying the invention.

Figure 2 is a longitudinal sectional view of the same.

35 Figure 3 is a transverse section thereof, and

Figure 4 is a detail top plan view of the lower bearing rollers and the carrying frame therefor.

The apparatus consists essentially of 40 axially parallel cleaner and bearing rolls 10 and 11 of which the former is carried by a shaft 12 while the latter, employed in duplicate to form a seat for a tube or flue 14, are carried by a bearing frame 15 fulcrumed 45 as at 16 to a suitable upright 17 of the supporting frame and yielding supported at the other end by a spring 18 or its equivalent, a handle 19 being connected with said frame for affording manual control of the bearing frame and hence enabling the operator to move the bearing rolls toward and from the cleaner roll as the operation of 50 cleaning the flues or tubes may require. The actuating spring for the bearing frame may 55 as shown be coiled upon a suitable guide

rod 20 which passes through the frame to maintain it in a proper path of movement as the bearing rolls are moved toward and from the cleaner roll.

A drive shaft 21 mounted in parallel relation with the shaft of the cleaner roll may have rotary motion communicated thereto by any suitable means such as the pulley 23, and motion is communicated from the drive shaft to the shaft of the cleaner roll by 60 means of intermeshing gears 24 and 25.

The above indicated shafts are mounted in suitable bearings in a supporting frame having the uprights or standards 26 connected by suitable longitudinal braces 27 65 and transverse braces 28, and for supporting the tubes or flue as they are successively presented to the cleaner roll and during the movement thereof with relation to the cleaner roll, there are employed rests 29 70 consisting of frames pivotally mounted as at 30 upon the uprights or standards of the main frame and provided with pivotal braces 31 for engagement at their lower ends with the transverse braces of the supporting frame, so that said end rests when 75 not required may be folded within the contour of the machine frame.

These end rests are respectively provided 80 with guide pins 32 and rollers 33, the former serving to maintain the flues or tubes in proper position as they are fed between the cleaner roll and the bearing rolls, and the said rollers serving to facilitate the movement of the tubes or flues over the rest 85 frame to prevent the offering of an excessive resistance thereto.

The cleaner roll is provided with surface ribs 35 serving in the rotation of the roll to cut into the scale on the surface of the 90 tube or flue and thus loosen the same and detach it from the surface, and preferably these ribs are spirally disposed to constitute a feed screw which serves to longitudinally 95 and slowly feed the tube or flue through the machine without requiring the constant attention of an operator. The yielding pressure afforded by the bearing rollers through the spring actuated supporting frame serves to maintain the tube or flue in such contact 100 with the spirally or screw ribbed surface of the cleaner roll as to insure such feeding movement of the tube.

Also preferably a protective hood 36 is 105 arranged over the frame work to prevent 110

flying particles of scale from injuring or annoying the attendant in charge of the machine.

Having thus described the invention, what we claim is:—

1. A boiler flue cleaner comprising a main frame, a rotary cleaner roll provided with a threaded surface, said cleaner roll supported by said frame, bearing rolls for holding a flue in contact with the cleaner roll, rest frames disposed at opposite ends of the main frame and adapted to support the extremities of a flue interposed between the cleaner and bearing rolls, and said rest frame being mounted to fold within said main frame when the machine is not in use.
2. A boiler flue cleaner comprising a supporting frame, a rotary cleaner roll provided with a threaded surface and mounted on said frame, a bearing pivoted at one end to the supporting frame and carrying bearing rolls for supporting a flue in contact with the surface of the cleaner roll, said bearing frame being provided with an opening adjacent its free end, a rod slidably ex-

tending through said opening, a spring surrounding said rod and bearing at one end against the bearing frame and yieldingly advancing the same, and means for communicating rotary motion to the cleaner roll.

3. A boiler flue cleaner comprising a supporting frame, a rotary cleaner roll provided with a threaded surface and having its spindle mounted on said frame, a bearing frame yieldingly advanced toward the cleaner roll and carrying the bearing rolls for supporting a flue in contact with the surface of the cleaner roll, a power shaft supported by said frame above the cleaner roll spindle, and means communicating rotary motion from the power shaft to the cleaner roll shaft.

In testimony whereof we affix our signatures in presence of two witnesses.

CARL A. VONDERHEID,
HERBERT L. EDDY.
